UNITED STATES PATENT OFFICE

ARNOLD RÜHE, OF BERLIN, GERMANY, ASSIGNOR TO INTERNATIONAL COMBUSTION ENGINEERING CORPORATION, OF NEW YORK, N. Y., A CORPORATION OF DELAWARE

BOILER PLANT

Application filed April 21, 1927, Serial No. 185,559; and in Germany April 22, 1926.

This invention relates to improvements in boiler plants and is especially useful in plants burning fuel in space, as, for example, pulverized coal.

5 One of the primary objects of the invention is to provide for improved circulation and distribution, especially where the combustion space is largely defined by tubes subject to radiant heat.

10 Another object of the invention is to provide an improved arrangement of boiler parts whereby it is possible to provide an effective combustion space largely formed by tubes subject to radiant heat to which heat is effectively transmitted, the remaining parts 15 of the boiler being located outside of the combustion space proper whereby it is possible to make such portions of any desired size without interfering with the combustion of 20 the fuel and without detrimentally affecting the heat transmission to the radiant heat tubes.

A more specific object is to provide the specific combination and organization of parts 25 hereinafter described.

More specific objects of the invention will appear hereinafter.

How the foregoing, together with such other objects and advantages as may herein- 30 after appear, or are incident to my invention, are realized, is illustrated in preferred form in the accompanying drawing, wherein

Fig. 1 is a sectional elevation of a boiler plant embodying the invention,

35 Fig. 2 is a sectional front elevation taken on line II--II and II'--II' of Fig. 1.

Referring now to the drawings, the reference character A denotes the combustion chamber of the furnace as a whole, and B 40 denotes the boiler as a whole.

Fuel is preferably admitted in the upper portion of the combustion chamber A by means of burners 1. Combustion air is supplied partly by means of the burners 1 thus securing prompt ignition of the fuel stream entering the combustion chamber and partly as secondary air. This secondary air is supplied through hollow compartment 2 and openings 3 in the furnace front wall, such 50 openings being distributed over the whole

front wall extension so that horizontal secondary air streams are introduced at different levels. Because of the boiler flue draft the flame takes a U-shaped path within the combustion chamber. The gases leaving the 55 combustion chamber are divided into two streams, each of which flows through suitably baffled banks of tubes arranged at the sides of the combustion chamber. Preheated air is preferably used as secondary combustion air and for this purpose is supplied to the compartments 2 in the furnace front wall by means of air boxes 10.

The downwardly flowing flame streams are surrounded by refractory walls in order to 65 secure prompt ignition and complete combustion of the fuel; the upwardly flowing flame streams, however, are surrounded by heat absorbing boiler elements.

The side walls in their rear extension and 70 the rear wall of the furnace are lined by boiler tubes. The boiler illustrated in the drawing comprises three upper drums 4 and two lower drums 5. The upper drums are arranged above the furnace chamber while the 75 lower drums 5 are located along the side walls and outside of the furnace chamber. The lower drums 5 are connected with the middle upper drum by means of banks of tubes 6 and with the outside upper drums by means of 80 banks of tubes 6b. These banks are suitably baffled, for example as indicated at 6a. The rear bank of tubes 6b constitute downcomers from the outside upper drums to the drums 5. The tubes of the banks of tubes 6 extend vertically upward from the drums 5 for a portion 85 of their length and then curve inwardly for connection into the upper middle drum so that, in effect, the vertical portion of these banks constitute side walls of the furnace and the upper curved portions constitute a roof for the furnace.

The furnace rear wall is lined by a row of tubes which connect the upper drums with a lower header 7 located outside the rear wall 95 of the furnace. The header 7 is connected with a header 9 located adjacent the front wall by means of tubes 8 forming a bottom cooling screen of the furnace chamber. The header 9 may be connected with the lower or 100

upper boiler drums for water feeding purposes as, for example, by downcomer means such as indicated at 9a in Fig. 1.

The tubes lining the rear furnace wall are 5 curved at their upper portions for connection into the upper drums so that they are equally spaced along the rear wall.

From the drawing it will be seen that because of the special arrangement of the boiler 10 tubes the radiant heat of the flame is transmitted directly to the boiler heating surface as much as possible. Thus I greatly increase the steaming capacity of a boiler installation of a given size and, by reason of the fact that the 15 walls of the furnace are lined with evaporating tubes, protection is afforded for the refractories of the walls, and, consequently, burning out the refractories is prevented. In fact, the only refractories exposed to the flame 20 which I employ are located in the region of fuel introduction and serve to aid ignition. It will further be seen that special cooling screens in the furnace are avoided and compensated by organic boiler parts so that the 25 boiler system is uniform and complications in the water-circulation are avoided.

Claim:

In a pulverized fuel burning boiler furnace, a combustion chamber, upright water tubes 30 forming the rear wall thereof, a plurality of upper drums, a pair of lower drums, banks of boiler tubes connecting the lower and upper drums, said banks including bent tubes extending upright for a portion of their extent 35 to form side walls of the combustion chamber and extending inwardly at their upper portions to form a roof for the combustion chamber, a lower header into which the lower ends of the rear wall tubes are connected, certain 40 of said rear wall tubes being connected at their upper ends into one of the upper drums and the remaining rear wall tubes being connected at their upper ends into the other upper drums, means for feeding water to the 45 rear wall tubes, and means for admitting fuel into the combustion chamber.

In testimony whereof I affix my signature.

ARNOLD RÜHR.
